UNITED STATES PATENT OFFICE.

LESLIE E. MOORE, OF LONG BEACH, CALIFORNIA.

AUTOMATIC ALARM APPARATUS.

1,210,348.

Specification of Letters Patent. Patented Dec. 26, 1916.

Application filed April 21, 1914. Serial No. 833,404.

To all whom it may concern:

Be it known that I, LESLIE E. MOORE, a citizen of the United States, residing at Long Beach, in the county of Los Angeles, State of California, have invented new and useful Improvements in Automatic Alarm Apparatus, of which the following is a specification.

This invention relates to an automatic alarm apparatus, and particularly pertains to a mechanism adapted to be mounted on automobiles to prevent theft of the latter.

It is the object of this invention to provide an alarm apparatus which can be readily attached to automobiles and power propelled vehicles, such as motorcycles, motor boats and the like, and which can be set to operate in event the vehicle is taken by an unauthorized person to sound an alarm and 20 cut off the motive power of the vehicle.

Another object is to provide an alarm mechanism of the above character which can be adjusted to operate to sound an alarm and stop the vehicle when the latter has traversed a predetermined distance, and which, when automatically operated, will effectively prevent further propulsion of the vehicle.

A further object is to provide an alarm attachment for power propelled vehicles 30 adapted to operate when the vehicle has been moved a certain distance to sound an alarm and to cut out the propelling mechanism, and in which adjustment can be effected, whereby the alarm will be sounded 35 at any suitable interval before cutting out the motive power.

A further object is to provide a means for setting and adjusting the alarm mechanism and for throwing it in and out of an operative position, which is controlled by a permutation mechanism to prevent its operation by those not familiar with the combination of the permutation device.

In carrying out the present invention I 45 provide a chain of speed reduction gears adapted to be operated by the fly-wheel of an internal combustion engine to advance a screw-threaded shaft carrying a revoluble member which rotates when the apparatus 50 is in operation and is adapted to operate when advanced by the screw-threaded shaft to actuate an alarm mechanism and subsequently cut off the flow of gas to the engine, and also break the electric circuit to the 55 spark plug; the above mechanism being incased in a housing and adapted to be shift-

ed to its operative or inoperative position through a permutation controlled device.

The invention is illustrated in the accompanying drawings, in which:

Figure 1 is a side elevation of the case and its contents, with the cover of the case removed and parts broken away. Fig. 2 is a vertical section on the line 2—2 of Fig. 1, as seen in the direction indicated by the arrows. Fig. 3 is a horizontal section on the line 3—3 of Fig. 1 on a reduced scale. Fig. 4 is a detail section on the line 4—4 of Fig. 1, as seen in the direction indicated by the arrows with parts broken away. Fig. 5 is 60 an enlarged detail section and elevation on the line 5—5 of Fig. 1. Fig. 6 is a section on the line 6—6 of Fig. 4. Fig. 7 is an enlarged detail section and plan view on the line 7—7 of Fig. 2. Fig. 8 is a horizontal section, with parts in elevation, on the line 8—8 of Fig. 1. Fig. 9 is an enlarged detail section on the line 9—9 of Fig. 1. Fig. 10 is a section and plan on the line 10—10 of Fig. 1 on a reduced scale. Fig. 11 is a detail 65 section in elevation on the line 11—11 of Fig. 1 on a reduced scale. Fig. 12 is a perspective view 70 illustrating the application of the invention. Fig. 12 is a perspective view 75 illustrating the application of the invention.

More specifically, 15 indicates a metallic housing or casing which is box like in form 80 and open on one of its sides to receive a sliding closure 16 the vertical edges of which are engaged in channels 17 formed on the inner faces of the side members of the housing 15; this closure 16 being designed to be 85 locked in its closed position to prevent access to the interior of the housing, as will be later described.

Mounted within the housing 15 and supported upon one of the side walls thereof is 90 a bracket 18, particularly shown in Fig. 1, the lower end of which is secured to a stud 19 by a screw 20 and the upper end of which is secured to a stud 21 by a screw 22. This bracket 18 is formed with a horizontal portion 95 extending from the stud 21, a portion which extends downwardly at an inclination, its lower end being bent at a greater angle as indicated by 23 to form an inclined face for guiding the movement of a frame 100 24 supported thereon. This frame 24 has a horizontally extending portion 25 formed with an opening 26 through which the bracket 18 extends in slidable contact therewith. The lower portion of the frame 24 110 is also formed with a horizontally extending member 27 having an elongated slot 28

therein through which the bracket 18 extends in slidable contact; the member 27 being normally arranged adjacent the upper end of the inclined portion 23 of the bracket, in which position it is sustained by means of a helical spring 29 wound on the bracket 18 and bearing between a pin 30 on the latter and the underside of the frame member 25.

10 The opening 26 is of such dimensions as to permit a rocking movement of the frame 24 in relation to the bracket 18 to the limits permitted by the slot 28; the frame 24 being normally held with the inner end of the slot 15 28 abutting against the outer face of the bracket 18 by means of a spring 31 which is secured at one end to the lug 19 and at its opposite end to a depending hanger 32 formed on the horizontally extending member 27 of the frame 24. The frame 24 is thus spring supported on the bracket 18 and is adapted to be shifted longitudinally thereof and rocked in relation thereto, which movements will be effected, as later described.

Formed on the member 27 of the frame 24 is a bearing in which a short shaft 33 is revolvably mounted; this shaft having a friction wheel 34 mounted on one end thereof, the periphery of which wheel is adapted to be projected by rocking the frame 24 through an aperture in the side wall of the case 15 into frictional engagement with the periphery of the fly-wheel 36 of an internal combustion engine. The opposite end of the shaft 33 is provided with a pinion 37 which meshes with a toothed wheel 38 formed on a stud shaft 39 carried by a suitable bearing on the outer end of the member 27 of the frame 24; the pinion 40 affixed to the toothed wheel 38 meshing with a toothed wheel 41 on a stud shaft 42 journaled in the bearing on the upper member 25 of the frame 24.

45 The toothed wheel 41 carries a beveled pinion 43 on its rear face which pinion meshes with a corresponding beveled gear 44 having a flanged hub 45 journaled in a bearing formed on the frame member 25.

50 The beveled gear 44 has a threaded central opening 46 therein adapted to receive a threaded shaft 47 held against rotation by means of a pin 48 thereon engaging a channel 49 on a rigid part of the frame 24 in such manner that when the beveled gear 44 is rotated the threaded shaft 47 will be advanced longitudinally therethrough.

Formed on the lower end of the shaft 47 is a collar 50 which is slidably engaged by a sleeve 51 adapted to rotate in relation to the threaded shaft 47 and to which sleeve is rigidly secured a shaft 52 arranged in alignment with the shaft 47 and having its lower end guided in an opening 53 formed in a horizontally extending member 54 on

the frame member 32. This shaft 52 is designed to be rotated independent of the threaded shaft 47 and irrespective of the longitudinal movement thereof. For this purpose a beveled pinion 55 is mounted on the shaft 52 and connected thereto by means of a screw 56 which is threaded in the hub of the pinion 55 and extends into a longitudinal channel 57 formed in the shaft 52 in such manner that the shaft 52 may be reciprocated longitudinally in relation to the pinion 55 and revolved on the rotation of the latter.

70 The rotation of the pinion 55 is effected by means of a beveled gear 58 mounted on the face of the toothed wheel 38. The lower end of the shaft 52 is formed with a laterally projecting finger 59 which is adapted, when the shaft 52 is lowered as later described, to intermittently strike a plate 60 75 adjustable vertically on a horizontally rockable sleeve 61 pivoted on a stud 62 and carrying a striker 63 normally held in contact with a gong 64 by a spring 65. The plate 60 is adjusted on the sleeve 61 by means of a thumb-screw 65' which passes through a vertically extending slot 66 in the plate 60 and engages a flange 67 on the sleeve 61. This adjustment of the plate 60 is provided for the purpose of disposing it in different positions in relation to the lower end of the shaft 52 so that it may be adjusted to be struck by the finger 59 to actuate the striker 63 to sound the gong 64 at various predetermined points in the downward movement 100 of the shaft 52.

Interposed in the path of downward travel of the shaft 52 is the arm 68 of a bell crank lever mounted on the stem 69 of a normally open cut-off valve 70; the other arm 71 of the bell crank lever extending upwardly and connected by a link 72 at its upper end to the lower end of a knife switch 73 pivoted at 74 on the side wall of the case 15. The valve 70 is disposed within the case 15 and connects at one side with a pipe 75 leading from a source of gas or hydrocarbon supply, as a tank 76, and connects on its opposite side with a pipe 77 leading to the carburetor 78 of the engine 79 for driving the vehicle indicated at 80.

110 The arm 68 of the bell crank lever has its outer end adjustable by means of a set-screw 81 by which the point of its engagement by the shaft 52 may be varied as occasion requires; this bell crank lever being designed to be operated by the downward movement of the shaft 52 to close the valve 70 and thereby cut off the flow of fuel to the carburetor 78 and engine 79 and simultaneously move the knife-switch 73 out of engagement with a contact 82, and thereby break an electric circuit through conductors 83 leading from one side of the magneto coil 84 of the contact 82, and a conductor 85 lead- 120 125 130

ing from the knife switch 73 to the engine spark plugs 86 which connect with the conductor 87 leading to the other terminal of the coil 84.

8 As before stated, the frame 24 carrying the mechanism for operating the shafts 47 and 52 from the fly wheel 36 through the friction wheel 34 is adapted to be rocked to move the friction wheel 34 in and out of 10 engagement with the fly-wheel 36. This rocking movement of the frame 24 is effected by means of a cam disk 88 pivoted on the horizontal portion of the bracket 18 with its peripheral edge normally bearing against 15 a friction roller 89 mounted on the upper edge of the frame member 24, as particularly shown in Fig. 4. This cam disk 88 is normally locked against movement and is 20 unlocked and operated by a permutation device to prevent unauthorized persons from manipulating the same to throw the alarm mechanism in or out of operation.

The cam disk locking means is particularly shown in Fig. 3, and comprises a series 25 of reciprocal rods, here shown as four in number, and designated as 90, 91, 92 and 93. These rods extend horizontally adjacent the upper end of the case 15 with their outer ends projecting therethrough and fitted with 30 finger engaging rings 94 by which they may be reciprocated longitudinally in an outward direction in opposition to springs 95 bearing between pins 96 on the rods, and a dependent hanger 97 carried by the top 35 plate of the case 15. The inner ends of any one or more of the rods normally project into sockets formed in the face of the cam disk 88; in this case the rods 90 and 91 being shown as normally engaging sockets 98 and 40 99, thus holding the cam disk against movement.

The inner ends of the rods 92 and 93 are connected to levers 100, as shown in Fig. 1, which in turn are connected to short bars 45 101 and 102 normally positioned out of contact with sockets 103 and 104 in the cam disk 88. The cam disk and the locking rods are concealed within the case so that it is necessary for the operator to know which one of 50 the rods 90, 91, 92 and 93, singly or collectively, must be pulled in order to release the cam disk. In this illustration the rods 90 and 91 comprise the locking rods and the rods 92 and 93 are the guards; these guard 55 rods operating when pulled, to advance the bars 101 and 102 into the sockets 103 and 104 in the cam disk so as to lock the latter against movement, from which it will be seen that if the rods 90, 91 and 92 are pulled 60 downwardly, while the cam disk is released by the withdrawal of the rods 90 and 91, it will be locked by the introduction of the rod 101 to the socket 103.

It is manifest that the number and arrangement of these rods may be carried out

almost indefinitely. To further guard against the wrongful operation of the cam disk 88 the latter is designed to be shifted when released from the locking bars by a specially constructed detachable hand hold 70 104. This hand hold is provided with a shank 105 adapted to extend through a slot 106 in the top of the case 15 and also through an aperture 107 in a peripheral flange 108 formed on the cam disk 88 with the lower 75 end of the shank 105 terminating adjacent the face of the portion of the bracket 18 in which the cam disk is pivoted.

The lower end of the stem 105 is formed with a cut-away portion 109, which, when the hand hold 104 and stem 105 thereon are turned to a predetermined position, will permit the stem to pass an abutment 110 mounted on the bracket 18 adjacent the cam disk 88, as illustrated in Fig. 5, and which abutment operates to engage the stem 105 to prevent rocking of the disk 88 when the stem 105 is not turned to its proper position.

To determine the necessary position of the stem 105 in order that the cut-away portion 109 will clear the abutment 110, a dial 111 is formed on the hand hold 104 and formed with numbered radial lines, one of which extends directly at right angles to the wall of the cut-away portion 109. In the illustration of this device in Fig. 6, this line is numbered 6, and when this line is positioned to extend in alignment with an arrow or other mark 112 formed at the outer edge of the slot 106, the cut-away portion will be 100 positioned as shown in Fig. 5 so that the stem 105 will pass the abutment 110. The hand hold 104 is held against displacement by means of a cotter-pin 113 which is passed through the stem 105 adjacent the underside 105 of the flange 108, as shown in Fig. 4.

In the application of the invention the case 15 is rigidly attached to the frame of the vehicle in such manner as to prevent its being easily removed and is arranged with 110 the opening 35 adjacent the periphery of the fly-wheel 36; flanges 114 on the case 15 on the marginal edges of the slot 35 projecting in close proximity to the periphery of the fly-wheel to prevent the introduction of implements for the purpose of interfering with the operation of the device.

Ordinarily the parts are disposed as shown in full lines in Fig. 1, that is, with the frame 24 in its uppermost position and friction disk 34 out of contact with the fly wheel 36. The threaded shaft 47 will also be in its uppermost position and the bell crank lever on the valve stem 69 will be disposed in its uppermost position by the action of a spring 115 120 125. When the parts are thus disposed the circuit from the magneto coil 84 to the spark plugs 96 is closed and the valve 70 is open to permit the passage of the hydrocarbon mixture from the tank 75 to the carburetor 78. 130

The engine 79 can be set in operation without affecting the alarm device.

When it is desired to set the alarm device to prevent theft of the vehicle the operator manipulates the hand hold 104 and the cam disk locking bars according to their combination so as to release the cam disk and position the hand hold so that it may be moved to rotate the cam disk and thereby cause the latter to bear downward on the upper portion of the frame 24 to shift the latter in opposition to the spring 29. The downward movement of the frame 24 causes the end of the slot 28 to ride over the underside portion 23 of the bracket 18 by reason of the pull of the spring 31, thus causing the friction disk 34 to move into contact with the fly wheel 36, in which position it is retained by the combined action of the spring 31 and the cam disk 88; the latter being rotated approximately one-quarter of a revolution, as shown in dotted lines in Fig. 2, to position its enlarged portion against the frame 24, in which position it is locked by the engagement of one of the locking bars with a socket 116 with sockets 117 and 118 positioned opposite the locking bars 101 and 102. When thus positioned the hand hold 104 will be turned so as to move the cut-away portion 106 out of alignment with the abutment 110 so that in event the locking bars are successfully disengaged from the cam disk the latter cannot be readily operated. However, the apparatus is designed to be concealed within the vehicle as much as possible and the gripping rings 94 of the locking bars are hidden beneath an overhanging shelf 119 so as not to be apparent to the ordinary observer.

The operation of the invention will now be as follows: Assuming that the engine 79 is set in operation by an unauthorized person with the intent of wrongfully using or operating the vehicle and that the device is adjusted as just described. The rotation of the fly-wheel 36 will act to revolve the friction wheel 34 which in turn will operate through the pinion 37, toothed wheel 38, pinion 40, toothed wheel 41 and pinion 43 to rotate the beveled gear 44 and the pinion 55, this latter being rotated by the revolving of the beveled gear 58 on the toothed wheel 38. The rotation of the beveled gear 44 will operate to advance the threaded shaft 47 in a downward direction, thus advancing the shaft 52, which will be rotated by the action of the pinion 55. The downward movement of the threaded shaft 47 is designed to be slow so as to permit the person driving the vehicle to travel a predetermined distance before the lower end of the shaft 52 will be advanced sufficiently far for the finger 59 to strike the plate 60. The unauthorized driver of the vehicle can thus travel a distance without being made aware of the presence of the alarm mechanism, which has been pre-

viously set by adjusting the plate 60 to operate at a predetermined distance of travel of the vehicle, which point is governed by the distance of the plate 60 from the lower end of the shaft 52. By this arrangement the alarm will be sounded when the vehicle is in motion and while occupied by the unauthorized person, thereby reasonably assuring the ascertainment and capture of such person, which ordinarily would not be possible were the alarm set off at the time of starting the engine. When the shaft 52 has been advanced downward a sufficient distance the finger 59 will strike the plate 60, thereby rocking the sleeve 61 in opposition to the spring 65 and causing the tapper 63 to rapidly strike the gong 64 to sound the alarm. Immediately thereafter the shaft 52 will move into engagement with the arm 68 of the bell crank lever to rock the latter downward so as to close the valve 70 and cut off the supply of gasolene to the carburetor simultaneously with the opening of the switch 73 to cut off the electric current to the spark plug, thus preventing further operation of the engine and necessitating stopping of the vehicle which cannot be again placed in condition for operation without readjusting the alarm apparatus so as to open the valve 70 and close the switch 73. To effect this adjustment it is necessary to open the slide closure 16, which is normally locked by means of one of a pair of reciprocal bolts 127 and 128 mounted in a guide 120 on the floor of the case 15; the bolts 127 and 128 being connected to the opposite ends of a short lever 121 pivoted at 122 and positioned by means of a spring 123 on the bolt 127 in such manner that one of the bolts will be normally disposed in an advanced position and the other in a retracted position. Connecting with the lever 121 is a cord 124, which passes around a direction roller 125 and is connected at its upper end to the lower member 27 of the frame 24 in such manner that when the frame 24 is in its lowermost position to relax the cord 124 the spring 123 will maintain the bolt 127 in its advanced position in engagement with a lug 126 on the underside of the closure 16 and when the frame 24 is in its uppermost position the bolt 127 will be retracted in opposition to the spring 123 and out of engagement with the lug 126 and the bolt 128 will be advanced into engagement with the lug 126 by reason of the lever 121. It thus becomes necessary to dispose the frame 24 in an intermediate position in order to arrange the bolts 127 and 128 both out of connection with the lug 126. This can only be effected by a person knowing the combination which will permit of the cam disk 88 being rocked to position the frame 24 in such intermediate position. By varying the lengths of the bolts 127 and 128 in relation to each

other different positions of the cam disk 83 will accordingly be necessary to position the bolts 127 and 128 clear of the lug 126. If desired, the lever 68 can be adjusted by means of the set screw 81 to operate in advance of the lever 60 so as to stop the vehicle without sounding an alarm, or it may be adjusted to operate at any desired time in relation to the sounding of the alarm.

10 By the use of this invention the proprietor of a power propelled vehicle can leave the vehicle unguarded with the assurance that in event it is maliciously taken that an alarm will be sounded and the vehicle automatically stopped within certain limits and by reason of the combination locking mechanism controlling the alarm mechanism the proprietor of the vehicle will have a secret combination lock for guarding the vehicle 15 against theft or improper usage.

What I claim is:

1. In an alarm mechanism for power propelled vehicles, the combination with a rotary member on the vehicle, of an alarm mechanism, a threaded shaft, a revolute shaft carried by said threaded shaft, means for advancing said threaded shaft, means for rotating the revolute shaft, and means on said revolute shaft for actuating the alarm mechanism when said revolute shaft has been advanced a predetermined distance.
2. In an alarm mechanism for power propelled vehicles, the combination with a rotary member, of a threaded shaft, means for slowly advancing said threaded shaft actuated by said rotary member, a revolute shaft carried by said threaded shaft, means for rotating said revolute shaft by the rotary member, an alarm mechanism, means on the rotary shaft for actuating the alarm mechanism, and means for throwing the threaded shaft and rotary shaft into and out of operative connection with said rotary member.
3. In an alarm mechanism for power propelled vehicles, the combination with a rotary member, of a threaded shaft, means for slowly advancing said threaded shaft actuated by said rotary member, a revolute shaft carried by said threaded shaft, means for rotating said revolute shaft by the rotary member, an alarm mechanism, means on

the rotary shaft for actuating the alarm mechanism, and means for throwing the threaded shaft and rotary shaft into and out of operative connection with said rotary member, and a permutation device controlling the operation of said last named means.

4. In a device for preventing the theft of power propelled vehicles, the combination with a rotary member on said vehicle, a case, a shiftable frame in said case, a threaded shaft adapted to be advanced in relation to said frame, a rotary shaft carried by the threaded shaft, a friction disk on said frame, means controlled by said disk for advancing the threaded shaft, means actuated by said disk for revolving the rotary shaft, means for shifting the frame to move the friction disk into and out of engagement with the rotary member on said vehicle, locking means to hold said last mentioned means in position such that the friction disk is engaged with said rotary member, and an alarm mechanism controlled by the advancement 70 and rotation of said rotary shaft.

5. In a device for preventing the theft of power propelled vehicles, the combination with a rotary member on said vehicle, a case, a shiftable frame in said case, a threaded shaft adapted to be advanced in relation to said frame, a rotary shaft carried by the threaded shaft, a friction disk on said frame, means controlled by said disk for advancing the threaded shaft, means actuated by said disk for revolving the rotary shaft, a cam disk for shifting the frame to move the friction disk into and out of engagement with the rotary member, an alarm mechanism controlled by the advancement and rotation 90 of the revolute shaft, permutation means for locking the frame against movement, reciprocal locking bars for engaging said cam disk to hold it against movement, a hand lever for operating the disk, and means co-95 operating with the hand lever for inhibiting movement of the cam disk.

In witness that I claim the foregoing I have hereunto subscribed my name this 9th day of April, 1914.

LESLIE E. MOORE.
